UNITED STATES PATENT OFFICE

2,604,929

DOUBLE TYPE OF HIGH CHAIR

Margaret Foley, Elmhurst, N. Y.

Application October 16, 1947, Serial No. 780,141

4 Claims. (Cl. 155—79)

1

This invention relates to high chairs for infants, but more specifically to means for accommodating two children on the same high chair support.

The main object of the invention resides in the provision of a high chair for infants having means for converting such a high chair into a twin high chair for accommodating two infants simultaneously or for having an extension table for convenient support of dishes, food and the like.

A further object of the invention resides in the provision of a high chair having additional seating means for another infant or having an additional supporting platform for food stuffs, clothing and the like.

A further object of the invention resides in the provision of an infant's high chair which is economical to manufacture, efficient in operation, simple to operate and aesthetic in appearance.

These objects and other incidental ends and advantages of the invention will hereinafter appear in the progress of the disclosure and as pointed out in the appended claims.

Accompanying this specification are drawings showing a preferred form of the invention wherein:

Figure 1 is a view in perspective and shows a conventional high chair in phantom in combination with an additional seat or support on the high chair frame.

Figure 2 is an enlarged side view in elevation of Figure 1 showing the means of collapsibility of the additional seat or support.

Figure 3 is a top plan view of Figure 1.

In accordance with the invention and the preferred form shown in the drawings, a conventional infant's high chair is shown in phantom having diverging corner supporting legs each designated by numeral 10 joined by conventional cross brace frames 11 and 12. At the upper ends of corner legs 10 the usual seating platform 13 is secured thereto with a back rest 14. The usual tray 15 is also provided as well as a foot rest not shown.

The rear supporting legs 10 of the high chair diverge sufficiently from back rest 14 as shown in Figure 2 to support the weight of a projecting seat and load thereon without causing the high chair to tilt rearwardly.

With the supporting frame of seat 13 and back rest 14 as mentioned, the invention contemplates the provision of a detachable auxiliary infant chair or extension supportable on and against the back rest 14. Thus the auxiliary chair is provided with a vertical frame work adapted to be detachably affixed to the high chair back rest 14

and to be supported thereagainst. Thus, the frame-work consists of a back rest 16 having a hand or finger gripping slot 17 therein and which joins a pair of supporting uprights 18 and 19 each having a hooked portion 20 and 21 respectively to engage the lateral ends of top edge 22 of the high chair back rest 14.

The framework of the detachable auxiliary chair as described sustains a projecting seat platform 23, a tray 24 spaced from and partly supported on platform 23 and a foot rest 25. The connections of the seating platform 23 to the auxiliary frame uprights 18 and 19, of the tray 24 to legs 29, 30 and legs 29, 30 to platform 23 and frame uprights 18 and 19, and of foot rest 25 to platform 23 are by means of hinges which permit the structure to collapse against the auxiliary chair frame as shown best in Figure 2 of the drawings.

Thus tray 24 is shown in the form of a frame having a table portion 26 and rearwardly projecting arms 27 and 28, the said frame along said arm portions having supporting legs 29 and 30 secured to platform 23. Tray arms 27 and 28 at the rear each have a hinge 31 secured to each of auxiliary chair uprights 18 and 19 for movement thereagainst. Seating platform 23 along the rear edges and at each end have a hinge 32 secured to the lower end of each of uprights 18 and 19 for movement thereagainst. Tray legs 29 and 30 at the upper end of each has a hinge 33 connected between the rear wall and the underside of each of tray arms 27 and 28 and at the lower end of each of said legs has a hinge 34 connected between the front wall of each of said legs and the upper wall of seating platform 23. Foot rest 25 at each end of the upper edge has a hinge 35 connected between the rear wall thereof and the underside of supporting seating platform 23.

Thus, the auxiliary chair comprised of the supporting framework 16, 18 and 19, the seating platform 23, the tray 24 and the foot rest 25 is capable of collapsing against the back rest 14 of the high chair as shown in Figure 2 and is also capable of removal from the high chair back rest 14 by lifting the device off the top edge 22. Although hinged connections are shown and described, the auxiliary chair may be connected together without the use of hinges, or partly with or without hinges so that for application to the high chair, the device may be applied at hook members 20 and 21 with all the parts in extended position and removed in the same way.

The tray 24 and the supporting seat 23 may be used for an infant while another infant is on

the high chair seat 13, the positioning of the children being back to back. In place of serving as a seat for an extra child on the high chair, the structure provides a platform for accessibility to an attendant for foodstuffs, clothes and the like. Two children may be fed and operated on at the same time by the attendant by the use of the device herein.

I wish it understood that minor changes and variations in the integration and location of parts may all be resorted to without departing from the spirit of the invention and the scope of the appended claims.

I claim:

1. In an infant's high chair having a seat and a back rest, an auxiliary chair supported on said high chair comprising a pair of attaching and spaced uprights supported against the back rest by hooks engaged with the upper end of the back rest, a seating platform secured to the lower ends of said uprights and projecting therefrom and a tray member secured between said uprights and the seating platform the seat of the high chair and the seating platform of the auxiliary chair being opposite and on the same level.

2. In an infant's high chair having a seat and a back rest, an auxiliary chair supported on said high chair comprising a pair of attaching and spaced uprights supported against the back rest by hooks engaged with the upper end of the back rest, a seating platform projecting from and movably secured to the lower ends of said uprights and a tray member movably secured between said uprights and the seating platform the seat of the high chair and the seating platform of the auxiliary chair being opposite and on the same level.

3. In an infant's high chair having diverging corner legs and a seat supported thereon and a back rest, an auxiliary chair supported on said

high chair comprising a pair of attaching and spaced uprights supported against the back rest by hooks engaged with the upper end of the back rest, a seating platform secured to the lower ends of said uprights and projecting therefrom and disposed for the greater part above and inside of the width of the lower ends of the rear diverging corner legs, and a tray member secured between said uprights and the seating platform the seat of the high chair and the seating platform of the auxiliary chair being opposite and on the same level.

4. In an infant's high chair having diverging corner legs and a seat supported thereon and a back rest, an auxiliary chair removably supported on said high chair comprising a pair of attaching and spaced uprights supported against the back rest by hooks engaged with the upper end of the back rest, a seating platform movably secured to the lower ends of said uprights and projecting therefrom and disposed for the greater part above and inside of the width of the lower ends of the rear diverging corner legs, and a tray member movably secured between said uprights and the seating platform the seat of the high chair and the seating platform of the auxiliary chair being opposite and on the same level.

MARGARET FOLEY.
